UNITED STATES PATENT OFFICE.

CHARLES N. ECKLYN, OF RACINE, WISCONSIN.

DESIGN FOR A CASING AND STAND FOR LIQUID-AGITATORS.

43,991.

Specification for Design.

Patented May 13, 1913.

Application filed October 12, 1912. Serial No. 725,530. Term of patent 7 years.

To all whom it may concern:

Be it known that I, CHARLES N. ECKLYN, a citizen of the United States, residing at Racine, in the county of Racine and State of Wisconsin, have invented a new, original, and ornamental Design for a Casing and Stand for Liquid-Agitators, of which the following is a specification, reference being had to the accompanying drawing, forming part thereof.

The figure is a perspective view showing my new design for casing and stand for liquid agitators.

I claim:

The ornamental design for a casing and stand for liquid agitators as shown.

CHARLES N. ECKLYN.
